ATTORNEY

UNITED STATES PATENT OFFICE.

ALEXANDER D. POLOUBOYARENOF, OF NEW YORK, N. Y.

DESIGN FOR A ROLLING BASKET.

51,989.

Specification for Design.

Patented Apr. 23, 1918.

Application filed December 5, 1917. Serial No. 205,673. Term of patent 7 years.

To all whom it may concern:

Be it known that I, ALEXANDER D. POLOUBOYARENOF, a subject of the Russian Government, residing at New York, in the county of New York and State of New York, have invented a new, original, and ornamental Design for Rolling Baskets, of which the following is a specification, reference being had to the accompanying drawing, forming part thereof.

In the drawing, the figure is a perspective view of the rolling basket illustrating my new design.

I claim:—

The ornamental design for a rolling basket, as shown.

ALEXANDER D. POLOUBOYARENOF.

Witnesses:

HUGH H. OTT,
A. V. DOYLE.
